UNITED STATES PATENT OFFICE.

JOSEPH V. ROBINSON, OF BRANFORD, CONNECTICUT.

AUTOMATIC TRAIN-PIPE COUPLING.

1,245,772.

Specification of Letters Patent.

Patented Nov. 6, 1917.

Application filed June 20, 1910, Serial No. 567,938. Renewed February 7, 1917. Serial No. 147,258.

To all whom it may concern:

Be it known that I, JOSEPH VINCENT ROBINSON, a citizen of the United States, residing at Branford, in the county of New Haven and State of Connecticut, have invented a new and useful Automatic Train-Pipe Coupling, of which the following is a specification.

This invention relates to automatic train-pipe couplers of the straight port type for railway cars, and among the objects thereof are to increase the strength, durability, and simplicity of construction, to insure certainty of action under all operative conditions, and to provide a structure characterized by the absence of all automatic valves or auxiliary devices which would tend to impede the flow of air or steam under certain conditions.

20 The invention comprises the novel features of construction, hereinafter fully described and claimed, and illustrated in the accompanying drawings, in which—

Figure 1 is a side elevation of a pair of coupling heads in the position they occupy when just about to engage each other; Fig. 2 is a vertical longitudinal sectional view of one of the coupling heads supported by the drawbar of the car, the upper and lower nipples which diverge from the vertical plane being shown in central section; Fig. 3 is a front elevation of the coupling head; Fig. 4 is a plan view of the same, partly broken away, and Fig. 5 is a diagram to be hereinafter described.

Throughout the following detailed description and on the several figures of the drawings similar parts are referred to by like reference characters.

40 The invention comprises an improved construction in which the coupler-head 10 is supported for universal movement, and normally maintained in coupling position, solely by a tapered tension spring 11 having the metal of its coils gradually decreasing in thickness, or weight, toward the apex, and positively secured at its apex and base to the coupler-head and a fixed support 12, respectively. The coupler-head is provided 45 with a series of integral pipe nipples 13, 14, and 15 diverging rearwardly in a common axial plane of said spring. As shown in Figs. 2, 3 and 4, all three of the series of pipe nipples 13, 14, and 15 lie in the same 50 longitudinal plane where they are connected to the head, and they diverge from one an-

other rearwardly in said plane where they emerge from the rear face of the coupler head, the forward ends of the outer nipples, adjacent the coupler head, being thus as close as possible to that of the intermediate nipple connection. For convenience of attachment of the hose sections the rear ends of the nipples 14 and 15 diverge laterally with respect to the common plane slightly in the rear of the said rear face, as indicated in Figs. 3 and 4. By virtue of this construction the small apex coil of the spring is seated closely and firmly between the forward ends of the series of nipples. 70

By this novel construction, the coupler-head is yieldingly supported for universal movement from its normal coupling position, in such manner as to present a minimum resilient resistance upon the initial engagement and movement of said head and a rapidly augmented resistance upon continued movement of the head to its interlocked and coupled position, thereby eliminating the danger of distortion or failure 80 of the coupler-heads by the troublesome battering action found to occur in previous constructions upon the initial contact of the heads, and insuring the maintenance of a perfect coupling under all practical conditions. 85

The aforesaid spring and diverging pipe nipples are employed in combination with a coupler-head of materially less face area than those necessitated in previous straight-port constructions for permitting efficient connection to the train pipe and unimpeded flow through the latter. This constitutes a highly advantageous feature of construction, which obviates all danger of perfect 95 coupling contact being destroyed by relative rocking of the engaged coupler-heads, and minimizes the strains to which the head guides are subjected in operation. When coupled the heads must remain firmly in 100 that position with respect to lateral movement, gapping, or rubbing of the faces one upon the other. The elimination of these defects without the use of cumbersome mechanism, such as hooks, dogs, etc., has been impossible with the common form of head, due to the excessive distance between the uppermost and lowermost ports—unavoidably associated with the design of the heads heretofore proposed—and to the manner of supporting the same. 105

To obtain a coupling between the heads,

without the use of cumbersome mechanism, that will remain firm and resist the lateral tendencies to disjoin or destroy it, it is necessary to reduce the head's area to the smallest 5 practical extent. This can be properly effected only by forming the tubular members so as to bring the openings therethrough at the points where the gaskets are inserted, nearest the head's center; by employing a 10 spring which will permit such design without departing from the tension necessary to effect a proper joint, and by the use of guides or gathering means 16 which have interlocking sockets sufficiently deep to 15 inclose and hold the heads firmly against lateral distortion similar to a close-fitting socket wrench inclosing a nut. Such sockets, however, must not be so great in depth as would injure the curvature of the guides if 20 the latter be kept within a practical operative dimension. For instance, guides of 25 practical weight and size with a socket 16' sufficiently deep to inclose and hold the ordinary coupler-head firmly, which is large and cumbersome, would be impractical in 30 form because the socket thereof would be so deep as to throw the angles of the guides almost parallel with the face. This would render them useless for bringing the heads 35 into alinement on a curve, or when one car is higher than another. But by reducing the head's area to the smallest practical extent, the depth of the sockets referred to may be greatly lessened and their efficiency increased, and the guides kept within practical 40 size. To illustrate, it is a well known principle that a wrench with parallel jaws, say one inch deep, will not grip a nut four inches in diameter with near the same firmness that it will grip a smaller one. But reduce the nut, say to two inches, and the same wrench will hold it rigidly without 45 turning independently or slipping therefrom. Hence by constructing the heads of the smallest practical area the depth of the 50 interlocking features and the size of the guides I have described can be kept within a practical dimension, and I thereby effect perfect gathering means and socket features, that will eliminate any liability of one head 55 tilting upon the other, tending to cause the ports to gap or leak. The effective interlocking depth of the head may be produced by a rearwardly extending flange 10', which 60 also increases the strength of the head in proportion to the weight of material. Further, by bringing the ports as near the center of the head as possible, and thereby reducing the latter's size, the effect of gapping 65 or lateral movement thereon is greatly reduced, due to the fact that the shorter the radius or the nearer the center of the heads the ports are brought the less movement will occur between coöperating ports with 65 the same angular displacement between the

faces. The purpose of the diagram, Fig. 5, is to illustrate the greater tendency for heads of large diameters to become separated and cause leakage than heads having smaller diameters. Considering *abce* to represent a socket and *abdf* to represent a head seated therein, the angle *cig* would indicate the possible separation of the faces of the heads due to the tilting of the inner head around the point *a* as a center, the point *g* 70 moving in the arc *dh* until it engages the wall *ce*. On the other hand considering *abc'e'* as the socket of a head of smaller diameter and *abd'f'* as the head seated therein, it will plainly appear that the angle 75 *c'ig'* will be materially smaller than the corresponding angle of the first example, even though the exaggerated distance *c'd'* remains equal to that represented by *cd*, the point *g'* in this instance moving in the arc *d'h'*. 80

The small end of the spring 11 is firmly seated between the extreme connections of the diverging series of connections above mentioned and there secured as by dogs 17, 90 and due to its small dimension, the practical feature of bringing the ports nearest the coupler head's center is made possible. The base of the spring is fixed to the bracket 12 as by dogs 18. At this point the greater 95 stress of supporting the head is brought to bear, and by tapering the metal of the spring in a suitable ratio with respect to the taper of its coils, the spring is caused to deflect more at the apex than at the base, thereby 100 producing a more flexible support and eliminating the troublesome feature of the base coil of the ordinary cone spring from taking a permanent set when used in this manner, due to nearly all the stress and yielding function 105 of the spring being brought to bear upon it.

The stem 13 of the coupling head is mounted slidably in a spherical member 19 journaled for universal oscillation in a socket 12' 110 of the aforesaid bracket, but prevented from rotation therein by lugs 13', thereby preventing irregular tension, or distortion, of the several supporting spring coils by angular movement of the coupler-head relative to 115 the axis of said spring.

I claim:

1. In an automatic train pipe coupler, the combination with a suitable support, of a coupler head, a spring carried by said support and having its forward coil secured to the rear of said coupler head, and nipples extending from the rear of the head above and below the spring and diverging upwardly and downwardly respectively, said nipples also diverging laterally from a vertical plane through the axis of the spring. 120

2. In an automatic train pipe coupler, the combination with a suitable support, of a coupler head, a spring carried by said sup- 125

port and having its forward coil secured to the rear of said coupler head, and nipples extending from the rear of the head above and below the spring and diverging upwardly and downwardly respectively, said nipples also diverging laterally in opposite directions from a vertical plane through the axis of the spring.

3. In an automatic train pipe coupler, the combination with a support and a tapering coiled spring extending forwardly from said support, of a coupler head connected to the forward or apex coil of said spring, said coupler head having rearwardly extending nipples immediately above and below said apex coil, the inner walls of said nipples abutting said coil and, in part, forming a seat for the same.

4. In an automatic train pipe coupler, the combination with a suitable support, of a spiral spring connected to and extending forwardly from said support, a coupler head having a central opening in its face, and a nipple extending rearwardly within the spring, said coupler head having openings in its face above and below and close to said

central opening and having nipples extending rearwardly from said upper and lower openings, said nipples diverging laterally and vertically, whereby they form suitable 30 hose connections without interfering with the action of the spring.

5. In an automatic train pipe coupler, the combination with a suitable support, of a coupler head, a central stem or nipple extending rearwardly from said head and flexibly carried by said support, a tapering spiral spring having its base coil secured to said support and its apex coil secured to said head, and nipples above and below said apex 40 coil and diverging upwardly and downwardly, respectively, from said central stem or nipple, the apex coil being seated in the crotches between said central stem or nipple and said upper and lower nipples.

In testimony whereof I have hereunto set my hand in the presence of two witnesses.

JOS. V. ROBINSON.
